UNITED STATES PATENT OFFICE.

MARGARETE NAUMANN, OF DRESDEN, GERMANY.

PROCESS FOR MANUFACTURING LACES AND LACELIKE PRODUCTS.

Application filed June 12, 1920. Serial No. 388,630.

(GRANTED UNDER THE PROVISIONS OF THE ACT OF MARCH 3, 1921, 41 STAT. L., 1313.)

To all whom it may concern:

Be it known that I, MARGARETE NAUMANN, a citizen of the German Republic, residing at Dresden, in the German Republic, have 5 invented certain new and useful Improvements in a Process for Manufacturing Laces and Lacelike Products (for which the following patents have been granted: In Germany, January 24, 1916, Patent No. 307,563; 10 Belgium, July 2, 1920, Patent No. 288,518; France, July 8, 1920, Patent No. 533,382; Great Britain, July 10, 1920, Patent No. 148,882, Italy, June 30, 1920, Patent No. 187,739), of which the following is a specification. 15 The novelty of the invention consists in the special method of manufacturing such products of threads which could hitherto be obtained only through working around solid cores or foreign bodies whereby the variety 20 of design is limited.

According to this invention the cores, consisting of wedge-shaped or cylindrical knots or bundles of threads, are obtained through 25 stepwise adding to one or several guide-threads in a manner which varies according to the design to be produced, threads which are to be used afterwards either in working-threads or as guide-threads, or through 30 stepwise separating such threads from a bundle of guide-threads placed in any convenient position or direction.

The wedge-shaped or cylindrical bundles of knots or threads are either used independently or in connection with flat lace-like 35 formations, so that no foreign bodies or cores are required. The consistence of the knots or bundles being obtained through the threads worked into the same so that they are adapted to give sufficient resistance to 40 the flat lace-like formation or to the hollow forms, into which they are worked.

The invention is illustrated in the accompanying drawings by way of example.

Figs. 1 to 15 show diagrammatically various forms of execution of the new lace-making-method.

In order to make the illustrations easier to understand the thread parts, which are designed to produce the wedge-form or roller form of the bundle, as well as the fastening points which hold the thread-bundles together, are shown as standing at a certain distance apart whilst in reality they are placed closely together. Further the threads

which issue from the sides of the wedge-shaped or roller-shaped bundles of knots or of threads, are shown as issuing at right angles with regard to the threads which have been added to or separated from the guide-thread or guide-threads whilst in reality they issue in any desired direction. The fastening-points are set off through black colouring, the guide-threads and guide-thread-bundles through hatching.

Figs. 1 and 2 show two ways of proceeding for the formation of wedge-shaped and roller-shaped bundles of knots or threads. Either the thread-ends f^1 to f^6 are bent off from a bundle b of guide-threads, placed according to requirement, stepwise one after the other, or the thread-ends f^1 to f^6 are added stepwise one after the other to a guide-thread s placed according to requirement, the bundles of threads thus formed being fastened either at the point r where a thread has been bent off or at the point a where a thread has been added. The fastenings s are either made with the thread which has just been bent off or with the thread which has just been added, or with threads from the bundle or with separate fastening-threads according to the above mentioned working methods which consist in winding, looping, plaiting, twisting, crossing, knotting or tying respectively.

Through the unilateral separation of thread-ends, according to Fig. 1, and through the unilateral addition of thread-ends according to Fig. 2, there are formed in each case a unilaterally wedge-shaped bundle of threads or of knots k , the size of which decreases from the head o towards the point s , if the threads are separated from the bundle, or from the point i towards the head o , if threads are added to the bundle. A certain part of the length of the thread is enclosed in the bundle k , the ends f^1 to f^6 protruding from the side of the bundle at r or at a respectively, the other ends g^1 to g^6 of said threads coming out of the head of wedge-shaped bundle. The guide-thread s which remains over when the threads are separated from the bundle or the guide-thread which was there before the threads were added issuing with the one end from the head of the wedge-shaped bundle and with the other end from the point of the same. This guide-thread can serve as a pull-

thread either for the pressing together of all the fastening points of the bundle, or to bring the knot- or thread-bundle from the wedge-shape into a stretched shape or into 5 any other shape according to the design to be produced.

The stepwise separating or adding of threads from the bundle or to the bundle can be effected at either side of the guide-thread 10 or of the bundle of guide-threads. The addition of threads at either side of the guide-thread is illustrated in Figs. 3 and 4.

Fig. 3 shows how the threads g^1 to g^6 have simultaneously added at either side 15 of the guide-thread.

Fig. 4 shows how two threads g^1 to g^6 are alternately added at either side of the guide-thread z .

Instead of thread-ends, whole threads can 20 be separated from or added to the bundles as shown in Figs. 5, 6, 7, 8 and 9.

According to Fig. 5 a double wedge-shaped bundle d e is formed through adding at 25 first thread-ends f^1 to f^6 to a guide-thread z in the manner hereinbefore described, and to separate said threads unilaterally as thread-ends g^1 to g^6 . The base o^1 of the part d of the bundle coincides with the base o^2 of the part e , the points i^1 and i^2 of said 30 parts being situated at opposite ends of said bundle.

To form a bundle k of the shape of an equilateral triangle as shown in Fig. 6 the ends f and g of threads are added at either 35 side to a guide-thread z , all the thread-ends coming out of the bottom of the triangle, the guide-thread passing through the apex and through the bottom of said triangle; it could however pass only through the apex.

Fig. 7 illustrates the unilateral addition of 40 two thread ends f and g to one guide thread z , both ends of every thread being simultaneously fastened for a part of its length upon a base. In this manner a unilateral 45 wedge-shaped bundle k is obtained the thread-ends of which come all out of the head o , the guide-thread z coming out at the head and at the point i .

As shown in Fig. 8 the unilateral addition 50 of threads bent over at the middle gives a unilaterally wedge-shaped bundle, the ends f , g of the threads coming out of the head o of the bundle, the guide-thread z coming out at the head o and at the point i .

Fig. 9 illustrates by way of example, how 55 through addition of threads at either side of a guide thread z an equilateral bundle is formed, the threads being alternately added to the guide thread, their ends f , g hanging out at the head side o of the handle.

The stepwise addition or separation of 60 thread-ends can further be executed in such a manner that several guide-threads or bundles of guide-threads are united. Such a 65 form of execution is shown by way of ex-

ample in Fig. 10. Through uniting the bundles b^1 to b^8 of guide-threads by plaiting and through equilateral separation of the thread ends f^1 to f^8 an equilateral wedge-shaped bundle of threads is formed, in which 70 the thread-ends f^3 can serve as guide-threads.

It is obvious that threads which have already been worked into bundles can be further added stepwise to other guide-threads 75 or can be separated again. Fig. 11 shows the addition of thread ends h coming from two different sides to form an equilateral triangular knot, the adjacent end threads of the two bundles serving as guide threads f g 80 for the new bundle to be formed, the other threads being added and fastened to the same from either side. The guide-threads could also be formed by independent, separate threads. The equilateral wedge-shaped bundle which is thus formed is suspended to the thread ends h .

Fig. 12 illustrates how the unilateral addition of thread-ends h is effected which come from one side, the first of the thread-ends being used as guide-thread. Any of the other thread-ends could however also serve as guide thread. The knot which is formed consists of a unilateral wedge-shaped thread-bundle suspended to the ends of the threads h .

The threads can further be cut off stepwise within the wedge-shaped or cylindrical bundle as shown in Figs. 13, 14 and 15.

According to Fig. 13 a cylindrical bundle w of knots or threads of uniform thickness is formed through cutting off stepwise at t the threads u^1 , u^2 , u^3 which have been added to the guide thread and through simultaneously adding stepwise other threads 100 v^1 , v^2 , v^3 which are also cut off at t , a new set of threads being added stepwise and so on. The first new thread v^1 is added so that it is in alignment with and of the first thread u^1 which is parallel with the guide-thread, the second new thread v^2 so that it is in alignment with the end of the second thread u^2 , the third new thread v^3 being in alignment with and of the third thread u^3 110 and so on. The circumference x of the cylindrical bundle w depends on the number of threads which are added each time.

According to Fig. 14 a unilateral wedge-shaped bundle of threads is formed through the stepwise separation of thread-ends g^1 120 to g^9 , the ends being then cut off directly behind the point where they are fastened, the ends t^1 to t^9 of the threads g^1 to g^9 being thus located in the bundle, the other ends projecting from the head of the bundle.

Fig. 15 shows how an equilateral wedge-shaped bundle k of threads is formed through 125 stepwise separating threads g^1 to g^4 from the guide-thread z the threads being cut off at the fastening points t , one end of the 130

threads being situated in the bundle, the other end projecting from the head of the bundle.

The stepwise adding or separating of threads to or from a guide-thread or a bundle of guide-threads can be raised according to the design of the lace to be made.

I claim:—

1. A method for the production of laces and of lace-like products consisting in adding, threads stepwise and successively to a guide thread so that thread bundles are produced, and in fastening the threads of said bundles together by means of one of said added threads.

2. A method for the production of laces and of lace-like products consisting in separating from a bundle of guide threads stepwise, threads designed to serve as working threads, in separating said working threads, and in fastening the remaining threads of the bundle of guide threads by means of said working threads.

3. A method for the production of laces

and of lace-like products consisting in separating from a bundle of guide threads stepwise, threads designed to serve as working threads, in separating said working threads forming new bundles of said working threads, and in fastening the remaining threads of the bundle of guide threads by means of said working threads.

4. A method for the production of laces and of lace-like products consisting in separating from a bundle of guide threads stepwise, threads designed to serve as working threads, in separating said working threads forming new bundles of said working threads, and in fastening the remaining threads of the bundle of guide threads by means of separate working threads.

In testimony whereof I affix my signature in presence of two witnesses.

MARGARETE NAUMANN.
